TOY

Crice L. Duley, Mounds, Ill., assignor of one-third
to William Duley, Mounds, Ill.

Application April 22, 1935, Serial No. 17,699

1 Claim. (Cl. 46—108)

This invention relates to toys of the mobile type and one object of the invention is to provide a toy of this character including a toy animal mounted upon a portable support and adapted to have motions imparted to it as the support is drawn along a floor or other surface and also including a figure representing a rider having movements imparted thereto by movements of the animal.

Another object of the invention is to so construct and mount the animal and also so mount the rider that as the toy is drawn forwardly, the rider will execute acrobatic movements and return to a position at rest upon the animal. Therefore, the rider will give a realistic representation of a bareback rider standing upon a horse and performing flip flops and other acrobatic movements.

Another object of the invention is to not only cause the rider to execute acrobatic movements, but also cause the animal to execute movements similar to those of a bucking horse and thus give the impression that the horse is attempting to throw the rider.

The invention is illustrated in the accompanying drawings, wherein

Figure 1 is a view showing the improved toy partially in side elevation and partially in section.

Figure 2 is a vertical sectional view, taken transversely of the toy along the line 2—2 of Figure 1.

Figure 3 is a section taken along the line 3—3 of Figure 1.

Figure 4 is a fragmentary view and illustrating a modified mechanism for imparting movement to the animal's hind legs.

Figure 5 is a section taken along the line 5—5 of Figure 4.

This improved toy is intended to be drawn along a floor, sidewalk or other similar surface, and has a base 1 carrying a bolster 2 adjacent its rear end to which the axle 3 of the rear wheels 4 is secured by staples or equivalent fasteners 5, it being understood that the rear axle may be rigidly secured against the bolster and the wheels turn about the axle, or the rear wheels fixed to the axle and the axle mounted for rotation. The front wheels 6 are fixed to ends of a crank shaft or front axle 7 which is journaled in bearing brackets 8 mounted at opposite sides of the platform, and by referring to Figure 2 it will be seen that the crank arm 9 of the shaft or front axle 7 is located substantially midway the width of the platform and directly below a slot 10 formed in the platform and extending longitudinally thereof. A yoke 11 formed of wire has its arms pivotally engaged in openings 12 formed through the forward end portions of the bearing brackets 8 and in order to limit downward movement of the yoke, there has been provided a cross bar 13 which

extends transversely of the platform under the yoke and has its ends secured to the bearing brackets so that it not only limits downward movement of the yoke but also serves to brace the bearing brackets. The intermediate portion of the wire is bent to form an eye 14 through which is loosely engaged an eye 15 at the rear end of a handle 16 which is also formed from a strand of stiff wire. It will be understood that the handle may be of any length desired which will permit it to be easily grasped by a small child and the toy drawn along the floor or pavement.

The toy animal has the configuration of a horse and consists of a body 17 formed at its front with a neck 18 and head 19, and while the body has been shown formed of wood and solid except for a passage 20 which extends diagonally from the rear end of the body at a downward incline toward the front of the body, it will be understood that the body could be formed of sheet metal with a passage formed through it by a metal tube or the like and also that the body could be formed of molded composition instead of being cut from wood. The front and rear legs 21 and 22 are disposed at the front and rear of the body at opposite sides thereof, the front legs being pivotally connected with the body by a pin 23 which extends transversely through the body and having their lower ends firmly secured by nails or equivalent fasteners 24 against opposite sides of a block 25 which is firmly secured upon the base 1 just back of the slot 10.

The body is to have pivotal movement relative to the front legs when the toy is in use, and in order to cause this motion to take place, there has been provided a pitman or elongated link 26 which is formed from a strand of stiff wire and has its forward end formed into an eye 27 loosely engaged about the crank 9 of the front axle and its rear end formed into an eye 28 loosely engaged about a pin 29 which extends transversely through the body adjacent the forward end of the passage 20. The pitman extends through the slot 10 and between the front legs of the animal, and by referring to Figure 1, it will be readily seen that when the toy is drawn forwardly and the crank shaft or axle rotated, reciprocating motion will be imparted to the pitman and cause the body to be swung vertically about the pivot 23. Therefore, the rear portion of the body will swing upwardly while the head moves downwardly, as indicated by dotted lines in this figure, and then return to the normal position shown in full lines. Therefore, the body will have movements imparted to it corresponding to those of a kicking horse.

The rear legs of the animal are also to have pivotal movement imparted to them during movement of the body so that they will simulate the movements of the rear legs of a kicking horse.

Therefore, the rear legs will be mounted and operated either as shown in Figure 1 or as shown in Figure 4. In Figure 1 the hind legs are pivotally mounted by a pin 30 which extends transversely through the body, as shown in Figure 3. Upper portions of the rear legs are connected by a pin 31 which passes transversely through the rear portion of the passage 20 and is engaged through arcuate slots 32 formed in the body and communicating with the passage 20 through opposite side walls thereof. A pitman rod 33 extends longitudinally in the passage 20 with its rear end formed into an eye 34 loosely engaged about the pin 31 and the forward end portion of the pitman 33 projects from the forward end of the passage and terminates in an eye 35 engaged about a pin 36 extending between and carried by the front legs 21. As the rod 33 is held against longitudinal movement relative to the front legs, movement of the body about the pivot 23 will cause movement of this pitman rod longitudinally in the passage 20 during motion of the body and, therefore, swinging movement will be imparted to the hind legs as the body moves and the motions of the body and hind legs will closely resemble those of a horse when kicking.

In the modified construction shown in Figure 4, the passage 37, which corresponds to the passage 20, is of greater width longitudinally of the body and the pin 31 and slots 32 have been omitted. The hind legs instead of being pivoted by means of a straight pin 30, are fixed to the squared end portions of a crank shaft 38 which is journaled through openings 39 formed in the body at opposite sides of the passage 37 and has its crank arm 40 disposed within the passage and loosely engaged by the eye 34 of the pitman rod 35. In this embodiment of the invention, the operation is the same as previously described, except that the pitman rod 33 is connected with a crank shaft to which the legs are firmly secured, whereas in the form shown in Figure 1 the pitman rod is connected with a pin 31 carried by the legs and slidably engaged through arcuate slots 32. In either construction, reciprocation of the pitman 26 as the front axle turns will cause the body of the animal to swing about the pivot 23, and as the body moves, the rear legs will be swung upwardly and then downwardly similar to the manner in which the hind legs of a horse are moved when kicking.

The rider has the configuration of a man and in the present illustration has been painted to represent a circus clown. The arms 41, which are bent at the elbow to extend forwardly with the hands 42 in front of the body 43, are rigid with the body but the legs 44 are pivoted to the body by a pin 45. A yoke 46 which is U-shaped and formed from a bent strand of stiff wire has its bridge portion loosely engaged through an opening formed in the hands 42 and at opposite sides of the hands carries spacing sleeves 47 which serve to hold the figure in a centralized position relative to the yoke so that the figure may swing about the bridge of the yoke, as indicated by the dotted lines in Figure 1. The arms of the yoke extend forwardly from the hands when the rider is standing upon the horse's back and are disposed at an incline with portions of the arms at opposite sides of the horse's neck.

The arms are disposed between pins 48 and 49 which project from the neck and head, and the extreme ends of the arms are bent inwardly to form fingers 50 which are loosely received in an opening or socket 51 formed transversely through the head at the inner end of the mouth of the horse. Therefore, the yoke will be pivotally mounted for swinging movement from the position shown in full lines in Figure 1 where its arms rest against projecting ends of the pin 48 when the rider is standing upon the horse's back to the position indicated by dotted lines when the horse kicks, as indicated by dotted lines in Figure 1. The yoke swings freely from the position in which it rests against the ends of the pin 48 to the forward position in which it rests against the ends of the pin 49 and as it stops with a jolt, the figure representing the rider will be caused to swing about the bridge of the yoke and the rider will perform a complete or partial flip flop. By the time the yoke strikes the projecting end portions of the pin 49, the body of the horse will be returning to the normal position in which the rear legs rest upon the platform or base and the yoke will then return to its normal rearwardly inclined position so that the rider will be returned to a standing position upon the back of the horse. It will thus be seen that when the toy is in use and drawn along a floor or sidewalk, the horse will have movements corresponding to those of a bucking or kicking horse and the rider will perform acrobatic movements such as turning flip flops and landing upon the back of the horse. The toy will afford a great deal of amusement to a small child, and as it is simple in construction and strong and durable it will not be liable to easily break or get out of order.

Having thus described the invention, what is claimed as new is:

In a toy, a base, a figure over the base representing an animal and including a body having a neck and a head at its front end, front and rear legs pivoted to the body, the front legs having their lower ends fixed to the base and the rear legs being free from the base, means for imparting tilting movement to the body about upper ends of the front legs and swinging movement to the rear legs, a rider over said animal having pivoted legs and forwardly projecting hands, a yoke straddling the neck of the animal and consisting of a bridge portion at its upper end loosely engaged through the hands of the rider to mount the rider for swinging movement about the bridge and arms extending from the bridge portion at opposite sides of the neck of the animal and at their lower ends pivotally connected with the head of the animal at opposite sides thereof to mount the yoke for swinging movement longitudinally of the animal, means to limit forward and rearward swinging movement of the yoke, the arms of the yoke projecting upwardly from the neck and head of the animal a distance greater than the distance between the hands and the upper and lower ends of the body of the rider whereby when forward movement of the yoke is stopped the rider may swing forwardly over the yoke and then downwardly and rearwardly through the yoke and upwardly and land in a standing position upon the back of the animal as the yoke moves rearwardly.

CRICE L. DULEY.
